[57] CLAIM

The ornamental design for a multifunction tool, as shown and described.

DESCRIPTION

FIG. 1 is a top plan view of a multifunction tool in a closed condition showing our new design;

FIG. 2 is a bottom plan view;

FIG. 3 is a left side elevational view, the right side being a mirror image thereof;

FIG. 4 is a front elevational view;

FIG. 5 is a rear elevational view;

FIG. 6 is a top plan view in an opened condition;

FIG. 7 is a left side elevational view of FIG. 6, the right side being a mirror image thereof;

FIG. 8 is a bottom plan view of FIG. 6;

FIG. 9 is a rear elevational view of FIG. 6;

FIG. 10 is a fragmentary top plan view of an alternate embodiment of the pliers jaws seen in FIG. 6; and,

FIG. 11 is a left side elevational view of FIG. 10.
